PULVERIZED FUEL FURNACE

Erich Dietzel, Cassel, Germany

Application March 12, 1930, Serial No. 435,343,
and in Germany March 22, 1929

4 Claims. (Cl. 110—104)

My invention relates to an adjustable burner arrangement for pulverized fuel furnaces, more particularly intended for locomotives.

In contradistinction to stationary boiler plants, the yield demanded of a locomotive boiler is subjected to very great variations at very short intervals, because for instance on stand-by or during downhill run, the demand sinks to a minimum amount while in starting or during uphill run, it increases very highly and quickly. These working conditions require a quick and efficacious adaptation of the furnace to the load of the fire chamber just prevailing, which adaptation in pulverized fuel furnaces can be attained in a very simple manner by regulation of the fuel quantities fed, which is effected by means of the fuel feeding device. To this end, hitherto, the pulverized fuel furnace has been subdivided into several individual burners adapted to be thrown in and out separately. First of all, however, it was necessary further, to provide in addition to this main burner an auxiliary burner, the object of which was to maintain in times of low demand, that is on stand-by or downhill run, the required boiler pressure and the flame, and to secure instantaneous re-ignition of the main burner for high demand. This auxiliary burner, however, requires not only a suitable place in the fire chamber but also separate ducts for the feed of air and pulverized fuel, a device for conveying the dust to the mixture duct and an agitating device with drive and control means. Now particular difficulties are encountered both as to construction and service by such an expensive appliance, which besides comprises a great number of parts, more particularly in view of the restricted room conditions in the pulverized fuel container on the tender of the locomotive and also in the fire box.

My invention therefore has for its object to avoid these drawbacks by the fact that an auxiliary burner with appurtenant feed duct, conveying and agitating device, drive and control therefor are entirely abandoned; and that in the main burner duct a second burner duct is arranged concentrically, which can be cut off by a suitable blocking member, so that either the external, annular duct with the appurtenant annular surface of the burner or this external duct in unison with the internal one, that is the whole burner is operative. I further preferably so subdivide the sectional areas of the ducts and the corresponding surfaces of the burner that the external annular duct with the annular burner

surface belonging thereto serves as an auxiliary burner, when the internal duct is cut off by the above blocking member. In order, further, that this inoperative central portion of the burner, which is then no longer cooled by the pulverized fuel-air mixture passing therethrough, is not injured by re-radiation of the auxiliary flame and of the fire box, I prefer to pass cooling air through this inoperative duct. This cooling air is supplied through the blocking member which, for this purpose, is hollow, and is effected in such a manner that when the blocking member is set to closing position, the cooling air is automatically admitted.

I further provide only one single conveyer adapted to feed both the small fuel quantity for the auxiliary flame and the much greater fuel quantity for the total burner. For the sake of adjustability, I provide a variable speed gear in the drive of the conveyer, in order to reduce the rate of revolutions of the latter when only the auxiliary flame is used, in accordance with the low fuel quantity required therefor. It will further be of advantage to couple with one another the control elements for the blocking member with those of the variable speed gear, to facilitate regulation by the crew.

Particular advantages are afforded by my improved burner arrangement in operating two main burners fed with pulverized pit coal. I have found by tests that pulverized pit coal can be burned satisfactorily only by adding a secondary supply of air. Then owing to the comparatively low quantity of conveying air, correspondingly small exit areas will be required on the burners which preferably are designed as so-called rose burners. Now it is my concentric duct arrangement which in many respects constitutes the most favorable solution in designing these small burner plates. Thus the burner surface exposed to the radiation heat is thereby reduced, this being a remarkable advantage in respect of the fire box temperature of 1600 degrees centigrade, which is much higher than that prevailing in burning pulverized brown coal. Furthermore, the efficiency of the burners can be regulated in a very simple manner within wide limits because of the fact that, as already mentioned, any desired quantity of pulverized fuel can be fed by adequately altering the rate of the conveyer movement even when the one burner duct is cut off from its fuel supply. In this arrangement therefore a special auxiliary burner is not required at all.

Moreover, my improved arrangement affords the advantage that the pulverized pit coal is very satisfactorily and quickly ignited when starting the engine, air being supplied only through the central burner, while dust-air mixture is blown in through the external, concentric burner. This good ignition is based upon the fact that by the addition of air through the central burner portion, both the air contact surface at disposal for the dust, and the radiation surface acting on the escaping mixture, are increased. These conditions result in the fact that pulverized pit coal, which is rather inert when compared with pulverized brown coal, may be ignited more quickly than hitherto.

In order that my invention can be more readily understood, an embodiment of my improved burner arrangement is illustrated in the accompanying drawing. Fig. 1 is a central longitudinal section through the parts concerned of the plant.

Fig. 2 shows in a larger scale a detail in the same manner as in Fig. 1.

Fig. 2a is a sectional view along line 2a—2a of Fig. 3.

Fig. 3 is a sectional view along line 3—3 of Fig. 2, and

Fig. 4 is an end elevation of the burner at the right of Fig. 1.

In this drawing *a* denotes the pulverized coal container fitted with a spiral conveyer *b*, adapted to convey the coal dust to a mixing chamber *c*. In this chamber, the air of combustion and the entraining air are fed through an air duct *d* which air with the dust streams through the burner duct *e* to the burner *f*, Fig. 4, which is arranged in the fire box *g* of the locomotive, indicated by dot and dash lines. A second duct *h* is concentrically arranged in the duct *e* and can be closed by a hollow breech piece *k* pivotally mounted on a pin *i*, the open position of this piece being indicated by a dot and dash line *k*¹. The hollow breech piece *k* is fitted upon its two sides with trunnions *i* and *j*, respectively, which are pivoted in bearings *r*₁ and *r*₂ respectively in the housing of the mixing chamber *c*. The trunnion *i* is made hollow and communicates directly with the interior of the breech piece *k*. The trunnion *i* is provided with four slotted openings *u* at its periphery adjacent its free end which are adapted to register with corresponding openings *v* in the bearing *r*₁. The slots *v*, in turn, open into the circular channel *w*, to which is connected an air pipe *m*. The trunnion *i* terminates in a square prism *t* upon which may be mounted a lever *s*. In the position of the lever *s* illustrated in Fig. 2, the breech piece *k* assumes the position illustrated in Fig. 1. In that position the slotted openings *u* and *v* register with each other, and the air passing from the air pipe *m* through the circular channel *w* is admitted to the interior of the breech piece *k* and the duct *h*, which is shut off from the mixing chamber *c*. Upon the shifting of the lever *s* in the position as indicated by dotted lines in Fig. 2, the breech piece assumes the position indicated at *k*¹ on Fig. 1. The circular channel *w* is separated from the interior of breech piece *k* and the air from air pipe *m* cannot pass into the interior of the breech piece. At this time also, the duct *h* is in communication with the mixing chamber *c*. When duct *h* is cut off from its fuel supply by the breech piece *k*, the remaining annular surface *f*¹, Fig. 4, of the burner *f* serves as an auxiliary burner, while

cooling air is admitted to the inoperative central burner portion from the air duct *m* through the hollow trunnion *i*, and through the hollow breech piece *k* and duct *h*. The variable speed gear in casing *n* is set so as to impart to the spiral conveyer *b* a suitably lower rate of revolution than that when the complete burner is operated. In the position indicated in the drawing, axially shiftable clutch collar *y*, engages loosely mounted gear *x*', which transmits the motion from the drive shaft *z*, upon which the collar is non-rotatably mounted, to counter shaft *z*'. The motion imparted to the spiral conveyer is reduced by suitable gearing *x*²—*x*³. In the position for a higher rate of feed the clutch collar *y* is shifted directly into engagement with gear *x*³, and thereby no speed reduction is effected upon the spiral conveyor. The control lever mechanisms for the breech piece *k* and the variable speed gear in casing *n* are interconnected as indicated by the connecting rods *o*, *p*, *q* in such a manner that when duct *h* is cut off, the lower transmission stage is set first in the gear casing *n* and only then is the breech piece *k* swung to closing position. Conversely when full burner operation is established, the duct *h* is opened first and then the gears in casing *n* are set to impart to the conveyer *b* a higher rate of revolution.

Although my improved burner arrangement is thought to be used primarily with pulverized fuel furnaces on locomotives, it is to be understood that it can be employed with the same advantageous effect in other types of boilers, such as marine boilers, stationary boiler plants, etc.

What I claim is:—

1. A pulverized fuel furnace comprising a burner subdivided into two concentrically arranged independent parts, two concentrically arranged fuel ducts each adapted to supply fuel to one of said burner parts, a fuel container, a fuel conveying means adapted to feed fuel from said container to said two fuel ducts, means for cutting off the supply of fuel to one of said two fuel ducts, means for adjusting the feed of said fuel conveying means in accordance with the different demand of fuel caused by said cutting off, control means for said cutting off means and control means for said adjusting means, and means for interconnecting said two control means whereby upon cutting off the supply of fuel to said one of said ducts, said cutting off control means operates subsequently to said feed adjusting control means, and conversely, in the opening of said one of said ducts to the supply of fuel, said cutting off control means acts prior to said feed adjusting control means.

2. A pulverized fuel furnace comprising a burner subdivided into two concentrically arranged independent parts, two concentrically arranged fuel ducts each adapted to supply fuel to one of said burner parts, a fuel container, a spiral conveyer adapted to feed fuel from said container to said two fuel ducts, means for driving said conveyer, a variable speed gear interposed between said conveyer and its driving means, control means for said gear, a pivotally arranged breech piece adapted to obturate one of said two ducts, means for controlling said breech piece, means for so interconnecting said gear control means and breech piece control means as to cause said gear to change over to transmission of a low rate of revolution first and said breech piece to obturate said duct
